DESIGN FOR A COMBINED WALLET AND MEMORANDUM PAD

Douglas J. Broughton, Springfield, Mass., assignor to Buxton, Incorporated, Springfield, Mass., a corporation of Massachusetts

Application June 3, 1948, Serial No. 146,742

Term of patent 14 years

(Cl. D87—3)

To all whom it may concern:

Be it known that I, Douglas J. Broughton, a citizen of the United States residing at Springfield, in the county of Hampden, and Commonwealth of Massachusetts, have invented a new, original, and ornamental Design for Combined Wallet and Memorandum Pad, of which the following is a specification, reference being had to the accompanying drawings, forming a part thereof.

Referring to the drawings:

Fig. 1 is a front perspective view of a combined wallet and memorandum pad embodying my new design;

Fig. 2 is a similar view with the memorandum pad in position for use;

Fig. 3 is a rear elevational view with one corner of the bill retaining pocket folded back; and

Fig. 4 is a front elevational view of the combined wallet and memorandum pad with the bill retaining pocket flap extended.

I claim:

The ornamental design for a combined wallet and memorandum pad, as shown and described.
DOUGLAS J. BROUGHTON.
